UNITED STATES PATENT OFFICE.

CHARLES S. CLARK, OF KEW GARDENS, NEW YORK.

GUIDE AND SCORE CARD FOR CONTROL IN PROGRESSIVE GAMES.

Application filed October 17, 1923. Serial No. 669,006.

To all whom it may concern:

Be it known that I, CHARLES S. CLARK, a citizen of the United States, and a resident of the suburb Kew Gardens, borough of 5 Queens, city and State of New York, have invented a new and useful Improvement in Guide and Score Cards for Control in Progressive Games, of which the following is a full, clear, and exact description, reference being had to the accompanying drawings.

This invention relates to means for properly coordinating the progression, and guiding the score, in the matter of games such as 15 bridge-whist played at a plurality of tables with a proportionate number of different players. While applicable in various respects to progressive games of different kinds, it is particularly advantageous for 20 guiding the progress of the entire tournament or affair involving a series of games in which, as in bridge-whist, it is desired to have different persons, and, in fact, each person play with each other person either 25 once or a set number of times.

More particularly the system of cards for guiding and scoring aim at what may be termed: "Every-player - your - partner - system",—and it is a system whereby every 30 partner has his individual card which is a complete guide for the entire tournament or party, so-called, directing exactly with whom each successive or progressive game shall be played.

Further objects of my invention are to provide guide and score cards which in some cases may border on the educational, but which, in any event, are formulated in a manner and by a system which have as the 40 primary objects utilizing terms which will be quickly remembered, terms which will be a novelty in conjunction with a card game and will catch the mind far better than mere numbers, also to set forth the guiding of the games or progression in a clear but still specific manner in order to simplify for all classes, even young players, the understanding of the guiding and scoring in such progression games.

With all, the guide or instructions contemplate the assurance of each player playing with each other one, and still eliminating the complexity and avoiding the chance of confusion, which has heretofore existed

in complicated methods of score or tally 55 sheets and cards suggested for such games, and, on the other hand, providing far more than, the simple score card having simply the serial places for the entry of each score during the progression. 60

While this invention may be practiced in numerous ways, a particular embodiment of my invention will be more fully understood with reference to the accompanying drawings, in which guide and score cards are 65 illustrated, and which drawings show:

Fig. 1 is a perspective view showing the front or title cover of the folder of a player's card.

Fig. 2 is an inside view of the folder with 70 the guide page for a score card for twenty players.

Fig. 3 is a view of the inside pages of a folder with guide and score pages for a 75 tourney of twelve players.

Fig. 4 is a similar view to Fig. 3, except the guide portion of the score card shows the alterations in the instructions, as applied to one other player in a game with twelve 80 players.

In Figs. 1 and 2 a folder is illustrated forming the score card, which on fold A has a flower design which is engraved, lithographed or suitably printed, and with a space arranged to give prominence to a 85 single flower-name C. This flower-name becomes the play-name of the holder of the score card. On the inside of the first fold or cover there again appears at C' the flower-name corresponding to that on the 90 front of the cover. Below this flower-name at C', follow nineteen specific instructions in a series, each paragraph D coordinated by a proper rule of the law of combinations, so that in sequence each paragraph D instructs 95 the player holding the card in direct clear language, exactly where and with whom he is to play each game in the progression of the tourney. Opposite the guide page, on fold E, are shown spaces F for the individual scores. At the bottom of this score page there may be space for the name of the holder of the card, as at B.

Figs. 3 and 4 show the inside of the cover and the inside of the back fold of a guide 105 and score card for twelve players. Here page A' has a space near the top where the name of the holder may be written, as at

B', the play-name appears at C', which in the case of Fig. 3 is "Daisy," and in the case of Fig. 4 C'', embodying the play-name "Ragged Robin." Thus the play-name C' 5 is followed by the series of eleven instruction sentences in plain clear language which have once for all been arranged in accordance with the law of combinations, and these guides D' following C' will be distinct, and 10 the guide sentences D'' following the play-name C'' will also be distinct and different from the guide card printed with any other play-name in the set. The inside of the 15 second fold E may carry the score spaces F, or in a single field card suitable space may be left in any other convenient way in harmony with the general arrangement and the specific objects of this guide and score card.

Thus as herein illustrated a series of play- 20 names are selected for the permanent arrangement of the guide card, of which each is the name of a flower, which is to be the identification of that particular player throughout the tourney. Below it follow 25 the paragraphs each couched in a clear sentence stating who the holder of that card is to play with at each step in the progression, and, furthermore, the table at which each progressive game is played, is designated by a number, or it may be words 30 identifying the different tables at the tourney. The adjacent sheet E, or part of the same sheet, has the blank lines F, which, in the particular form illustrated, would be 35 opposite each paragraph of the guide designating the progression control. These score places F may, however, be spaces left in close proximity and on the same field or face of the card where the guiding paragraphs are engraved or printed, illuminated 40 or otherwise provided in attractive and clear form.

In order that twelve different players shall carry through a tourney of bridge-whist in 45 which "Every-player-your-partner" is assured,—it will thus be seen that there will be twelve cards and each one different so far as the title C' and the guiding text D' are concerned. To this extent there would 50 be twelve cards in the case of there being twelve players or contestants, but by the designation before the commencement of the tourney or party each person would be designated, in the case herein illustrated, by 55 a play-name of a flower, and thus entire sets can be prearranged and printed carrying through the series of play-names, and before the play begins the parties may receive a flower corresponding to their card, 60 or on the reverse of the card, or on the outside of the folder there can be attractively illustrated the flower corresponding to the play-name the holder of the card is to assume and by which she or he is to be guided 65 throughout the progressive game.

It will, furthermore, be seen that the selection of flower names for example, will in the first place be catch names more readily memorized than it is possible for a large number of guests to remember surnames, so 70 that the system involves an element with which can be interwoven certain attractive features of a tourney or party, and still far more readily create instant identification of players by names that are on every 75 tongue and easy to associate in conjunction with the progress of games, even with the young as well as the old.

When sixteen or twenty players are involved the designation of the different players and their successive partners, as well as their progress from place to place during the tourney, are determined once for all by those making these novel score and guide cards,—and such determination involves the 80 principle of permutation and combinations well known in mathematics, so that when once arranged or set up as to the combination, by a recognized mathematical formula or by simple practical work out well known 85 in the art, it thereupon becomes a matter of reducing what would be otherwise far too complicated matters for the ordinary player to cope with, into the simplest possible formulas, namely, clear sentences or phrases 90 designating unequivocally how each step in the progress of each player throughout the tourney shall follow in its right succession in order to have harmony and save time, and withal to assure that "Every-player-your-partner" 95 is carried out with the utmost simplicity.

While in the drawings herewith, a set of score and guide cards are referred to by two samples, in which flower names are used, it 105 will be understood that a series of the required number of gem names may be used, such as designating each player, for example, as emerald, ruby, turquoise, diamond, etc. Or for peculiar reasons, such as a 110 tourney involving literary people, they might designate each player by the name of a well known author; and in this manner a variety of different basic characters, either natural, such as flowers, minerals, animals, 115 birds, etc., or personal or geographical names may be utilized, and a variety of sets of cards may be provided for general use to suit particular conditions and circumstances which would make one or the other set-up 120 more attractive, more convenient or more feasible.

Likewise the association of the score with the guide paragraphs may be varied in many ways from what is herein particularly 125 shown.

In particular, it is to be noted that complete sets for any given number of players or progressive games, such as bridge and other cards, are, by the practice of this in- 130

vention, provided in a manner insuring a clear understanding, a clear scoring and a clear guiding of the progress of the tourney, most readily appreciable for all those participating in such games.

While many variation may be made in form of cards, and the designation of parties, the selection of play-names, and in other details, without departing from the spirit of 10 my invention, what I claim and desire to secure by Letters Patent is:

1. A series of guide cards for games of a progressive tournament, comprising a series of engraved, printed or like permanent guide 15 forms including throughout a predetermined set of common-subject names as play-names, successive directions each coupling a play-name with the progressive order of games, and a different title on each card consisting 20 of one only of said play-names.

2. A set of cards for control of progressive tournaments comprising a coordinated series of cards each having a different set of guiding instructions coordinated with the 25 other cards of the set and consisting of a series of paragraphs specifically directing the holder of each card with respect to the playing of each successive game, embodying in each directing paragraph a distinctive 30 play-name as one of a series of common-subject names, and a single one of said common subject names forming the permanent title of each guide card, and a like cover title name permanently identified with said 35 card.

3. A progressive bridge-whist score and guide card consisting of a tabulation of instruction paragraphs headed by one of a predetermined series of common-subject 40 play-names, said paragraphs coordinated and forming a series of guiding steps in specific form reciting the players and the table at which the player is to progress throughout a tourney, with each successive name under the predetermined play-name.

4. A series of progressive bridge-whist guide cards comprising a set of cards in

which each individual card has a title illustration respectively representing one in a series of permanently established common-subject play-names, a tabulation of guiding directions indelibly associated with one of the respective play-names differing in each card and coordinated throughout the series of cards each in turn specifically setting 55 forth on each card the successive order of play of individuals and tables, and a score field associated with each order of play.

5. A series of progressive game guide cards, comprising a coordinated series of individual cards for each of a predetermined number of players of a tourney, having engraved, printed or like permanent instructions including a distinctive and different common-subject play-name on each of the 60 cards of the series, and a schedule of directions, differing on each card, specifically ordering the progress of play for each successive game, and embodying in said guiding directions all of the predetermined play- 65 names of the set except the one play-name title of its respective card.

6. A plurality of cards constituting a series for use in a progressive card tourney, comprising a coordinated set of cards 75 for a predetermined number of players in the tourney, a series of directions on each card and each series on every card differing from those on the other card and in each case constituting the guiding instruc- 80 tions with respect to the individual card, a common-subject name forming the title for each series of guiding directions, and other players and cards identified throughout the instructions by other play-names in the same 85 series of a common-subject, and a cover title on each card indelibly carrying the corresponding play-name, and embellishment of the cover characteristic of the title play-name.

In testimony whereof, I have signed my name to this application this 10 day of October, 1923.

CHARLES S. CLARK.
